[57] ABSTRACT

A support for a pulling device for use in repairing automobile frames and the like. A pair of horizontally disposed elongated legs are pivotally connected together for swinging about a vertical axis and support a vertically extending post on which the pulling device is mounted. The arrangement of the legs provides a stable base permitting the pulling to be directed at various angles horizontally and vertically.

**APPARATUS FOR STRAIGHTENING
AUTOMOBILE FRAMES AND THE LIKE**

This invention relates to apparatus for repairing automobile frames and the like and is in some respects similar to the apparatus shown in U.S. Pat. No. 3,398,565 dated Aug. 27, 1968. The present device is considered to be an improvement over the patented apparatus.

Heretofore various types of apparatus have been devised to permit exerting relatively large forces on the body or frame of an automobile during the repair of such automobile. Many of such prior art devices require numerous changes in the setup of the apparatus when it is required to change the directional pull of the pulling device. Such changes in the setup are time consuming thereby adding to the expense of the operation.

The main object of the present invention is to improve the versatility of the repair apparatus and at the same time make the apparatus portable so as to be more readily adaptable to use under different situations.

Another object of the invention is the provision of a support for the pulling device which is light weight and at the same time extremely rigid.

Yet another object of the invention is the provision of a support for the pulling device which is more versatile than prior art devices of like nature in that once the apparatus is set up in a stable manner, the direction of pull may be widely changed both in a horizontal direction and in a vertical direction.

Further objects of the invention will be apparent from the following specification and from the drawings.

FIG. 1 is a side elevation of the preferred form of the invention.

FIG. 2 is a horizontal sectional view taken in a plane indicated by lines 2—2 of FIG. 1.

FIG. 3 is a side elevation of the pulling device.

FIG. 4 is a top plan view of the pulling device.

FIG. 5 is a fragmentary plan view of an automobile frame showing one application of the invention.

FIG. 6 is a view similar to FIG. 5 showing another application of the invention.

FIG. 7 is an isometric view of the abutment means.

FIG. 8 is an isometric view of the connection between the cross bar and one leg of the support apparatus.

FIG. 9 is an isometric view of a combination abutment and clamp for securing a cross bar to the pinch weld of an automobile body.

In detail and first with reference to FIGS. 1 and 2, the invention comprises a base assembly which includes a pair of elongated legs generally designated 1, 2 respectively, each of which is preferably formed from tubular material having a rectangular cross section. As best seen in FIG. 2, leg 1 is provided adjacent one of its ends with a pair of hinge elements 3, 4 which are preferably welded to the sidewalls of leg 1. Leg 2 is provided at one of its ends with a complementarily formed hinge element adapted to cooperate with hinge element 3 so that the legs 1, 2 may be pivotally connected together by a hinge pin 5. In FIG. 2 leg 2 is shown swingably connected to leg 1 on one side of the latter so that it may be folded to an inner position represented by the dot-dash line and alongside the leg 1 when it is desired to store the apparatus. By the above described structure, it will be apparent that leg 2 may be removed from the hinge element 3 and transferred to the opposite side of

leg 1 to the position shown in dotted lines in FIG. 2. Leg 1 is preferably provided with an extension 8 which is telescopically received within leg 1 and a similar extension 9 is telescopically received within leg 2. Depending upon the effective length desired, these extensions may be fixedly secured relative to the main leg by providing through holes 10, 11 in the leg and extension respectively (see FIG. 1). A pin 12 may be passed through registering holes so as to fix the extension in any desired position. Each leg 1, 2 is preferably provided with ground wheels 7.

Extending upwardly from leg 1 and fixedly secured as by welding thereto, is a post 15 of circular cross section. Brackets 16, 17 may be welded to post 15 and leg 1 to provide additional stability for the post. The post 15 serves to support a pulling device generally designated 18 which is very similar to the pulling device disclosed in U.S. Pat. No. 3,398,565 dated Aug. 27, 1968 and to which patent reference is made for details not disclosed herein. By the present invention the pulling device 18 is connected to a sleeve 19 slidably supported on the post 15. Another sleeve 120 is provided under the sleeve 19 so that the pulling device 18 may be positioned in any desired location along the vertical extent of the post 15. Said sleeve 120 is provided with a locking screw 121 to permit the sleeve 120 to be secured to post 15 in any desired position thereby positioning the pulling device 18 at any point along the length of the post 15. It will be noted that the pulling device 18 disclosed herein, unlike that disclosed in U.S. Pat. No. 3,398,565, may be swung in a horizontal plane to obtain whatever angularity is desired with reference to the post 15.

One application of the invention is given by way of example in FIG. 5 wherein longitudinally extending frame members 20, 21 of an automobile are shown. If it is desired to exert a pulling effort on a distorted portion 22 of the frame 21 for example, the pulling device 18 may be connected by means of a chain 23 with a hook 24 engaging the portion 22 of the frame 21. By spreading the legs 1, 2 apart to the general position shown in FIG. 5 the frame member 20 may be engaged by brackets 25. One of these brackets 25 is shown in FIG. 7 and comprises a base plate 26 supported on leg 1 or leg 2. Extending downwardly from the outer side edges of base plate 26 are a pair of side plates 27 which fit along the vertical side walls of the leg 1. Said side plates 27 are provided with rectangular openings 28 which extend below the bottom side of leg 1 so that a wedge 29 may be driven through the apertures 28 and into tight engagement with the bottom side of leg 1, thereby firmly securing the bracket 25 relative to the leg 1 or leg 2.

Swingably secured to base plate 26 by a pivot 31 is the horizontal leg of an angle 32 and which horizontal leg is provided with an arcuate slot 33 through which projects a bolt 34 secured as by welding at its lower end to the base plate 26. A nut 35 cooperates with bolt 34 so that the angle 32 may be set in whatever desired angular position is required to engage the frame 20 or similar structure. By tightening the bolt 35 it will be seen from FIG. 5 that the brackets 25 may be firmly set against the frame 20 to offer resistance to the pulling effort exerted by the pulling device 18.

To assist in preventing the spreading apart of legs 1, 2, a chain 40 may be provided which is connected at one end to a hook 41 carried by a sliding saddle 42 which may be fixedly secured to the extension 9 for ex-

ample, of leg 2 by means of a wedge (not shown) in a similar manner to the wedge 29 of FIG. 7. Similarly, the other end of chain 40 may be connected to a hook 44 carried by another saddle 45 on the extension 8 of leg 1.

It will be apparent from FIG. 5 that the supporting structure for the pulling device 18 is extremely stable due to its closed triangular form and that a substantial pull may be exerted by pulling device 18 with the reaction thereof borne by the legs 1, 2 and transferred through brackets 25 to the frame member 20.

Another example of the operation of the invention is shown in FIG. 6 wherein the frame members 20, 21 are indicated and it is desired to exert a pulling effort on one distorted end 46 of the frame 21. In this case the leg 1 has mounted thereon a bracket 25 for engaging the frame member 21 as indicated in FIG. 6. The other leg 2 of the supporting structure is positioned substantially parallel to the frame member 20 and a pulling effort is directed transversely of the automobile through chain 23 and hook 24. In this case the support for the pulling device 18 may be rigidly held in place relative to the automobile by means of cross bars generally designated 50. One of these cross bars is shown in FIG. 8 and comprises a pair of elongated tubular elements 51 of rectangular cross section spaced apart to provide a space therebetween and fixedly secured together at their ends by means of end plates 52. A typical connection for connecting a cross bar 50 to one of the legs 1, 2 is shown in FIG. 8 wherein a saddle member 54 is provided on leg 1, for example, and fixedly secured to said leg by means of a wedge 55. The upper side of saddle 54 is provided with a nut 56 which cooperates with a threaded bolt 57 which in turn is welded at its upper end to a block 58. This block 58 is apertured to receive a wedge 59 therethrough so as to fixedly but releasably connect the cross bar 50 to the leg 1 or the leg 2.

As seen in FIG. 6 a cross bar 50 may be fixedly secured by the structure shown in FIG. 8 to legs 1 and 2 so as to provide a rigid structure and to prevent the legs 1, 2 from moving relative to each other. In addition the above described structure may be connected to the automobile body itself by a clamp generally designated 65 and illustrated in FIG. 9. This clamp 65 comprises a base plate 66 to which is welded an upstanding flange 67 which is held rigidly relative to base plate 66 by means of gusset plate 68. In some applications the side of flange 67 opposite the gusset plate 68 may be used as an abutment against one of the frame members 20, 21 of the automobile. In order to permit securement of the bracket 65 to the automobile body, a pair of elongated clamping bars 70, 71 are provided. Bar 70 is welded along its lower edge to the upper edge of flange 67 and bar 71 is secured to bar 70 by means of bolts 72 by passing through bar 71 and threadedly engaging suitable threaded apertures in bars 70.

As is well known, the typical automobile is provided with a downwardly projecting pinch weld flange of sheet metal along the opposite outer longitudinal sides of the vehicle. Such pinch welds are indicated schematically at 75 and 76 in FIG. 6. By means of the clamp 65, the clamping jaws formed by the bars 70, 71 may be positioned on opposite sides of the pinch weld 75, 76 and tightened to the automobile body.

The flange 67 and gusset plate 68 are cut away to provide an opening for receiving a nut 78 in which is threadedly secured a downwardly extending bolt 79 which is welded at its lower end to a block 80. By this

structure the bracket 65 may be secured to the cross bar 50 at any degree of angularity by driving a wedge 81 through the block 80. Thus as seen in FIG. 6, a cross bar 50 may be secured to leg 2 by means of the clamping structure shown in FIG. 8 and also secured to the body of the automobile by means of clamps 65 secured to the pinch welds 75, 76. Also as shown in FIG. 6, the clamp 65 can secure another cross bar 50 which in turn is secured to both legs 1 and 2.

The above described structure not only results in a portable support for the pulling device 18 which may be readily positioned in any desired location with respect to the automobile, but said support, including the legs 1 and 2, may be firmly secured to the automobile body so as to provide optimum resistance to the pulling effort of pulling device 18.

I claim:

1. A support structure for mounting pulling apparatus for use in straightening automobile frames and the like, comprising:

a base assembly,

said base assembly including a pair of ground supported horizontally disposed elongated legs,

means on said base assembly for pivotally connecting said legs together at one of their corresponding ends for swinging said legs toward and away from each other about a vertical axis, a vertically disposed post secured at its lower end to said base assembly,

means on said post for securing thereto a pulling device adapted to be connected to a portion of an automobile frame,

abutment means on one of said legs for engaging a portion of an automobile frame for resisting the pull of said pulling device, and

means on the other of said legs for connecting the same to a fixed object.

2. A support structure according to claim 1 wherein

40 said legs are each provided with ground wheels to facilitate moving said legs under the frame of an automobile.

3. A support structure according to claim 1 wherein one of said legs is tubular and includes an extension 45 telescopically received within said one leg, and means for securing said extension relative to said one leg.

4. A support structure according to claim 1 wherein a tension member is provided, means on said legs connected to opposite ends of said tension member for limiting movement of said legs away from each other.

5. A support structure according to claim 1 wherein a saddle is provided on one of said legs, means for fixedly securing said saddle in a predetermined position along the length of said one leg, said abutment means being pivotally supported on said saddle to permit positioning said one leg at different angles to the portion of the frame engaged by said abutment.

6. A support structure according to claim 5 wherein said means for fixedly securing said saddle comprises a wedge adapted to engage a side of said one leg.

7. A support structure according to claim 1 wherein said post is circular in cross section, a sleeve slidable on said post, said pulling device being mounted on said sleeve and swingable therewith horizontally to different angular positions relative to said post.

8. A support structure according to claim 1 wherein a cross bar is provided extending between said legs, and means for securing said cross bar to said legs.

9. A support structure according to claim 8 wherein
means is provided for securing said cross bar to the

body of an automobile.
